CUSHIONING DEVICE

Emil H. Blattner, Rochester, N. Y., assignor to
The Symington-Gould Corporation, Rochester,
N. Y., a corporation of Maryland

Application June 23, 1938, Serial No. 215,480

25 Claims.

(Cl. 267—9)

The invention relates to cushioning mechanisms or devices for use in a railway vehicle and being particularly adapted to function as means for assisting in resiliently supporting a bolster or load carrying member from an associated side frame as well as dampen, disturb or break down synchronous or harmonic actions in associated bolster supporting springs.

Heretofore cushioning devices of the present character were designed to employ release springs having a normal height less than an Association of American Railways standard spring with the result that the devices required special release springs.

An object of the present invention is to provide, in a cushioning mechanism, a release spring having a normal height substantially equal to the normal height of an American Association of Railways standard spring so that the spring may either be used in combination with a cushioning device or, if so desired, employed in combination with a spring of the same character.

Another object of the invention is to so construct and arrange a cushioning device as to resiliently and frictionally resist an initial compressive movement of the device and, after a predetermined compressive movement thereof to energize an additional resilient element.

A feature of the invention is the provision, in a cushioning device, of a shell member having portions of complementary segmental shoes extending within the shell member and adapted to be urged radially of the device into bearing relation with said shell member by means of an axially disposed cylinder formed of a resilient material; the cylinder and shoes having a follower member associated therewith so that, after a predetermined compressive movement of the device, the shell member will actuate the follower and energize the cylinder.

Another feature of the invention is to arrange the cylinder, shoes and follower in such a manner that when the follower is actuated and the cylinder is energized, shear stresses will be developed in the cylinder.

These as well as numerous other objects and features will become apparent from the succeeding detailed description of the invention which is to be considered together with the accompanying drawing, the latter of which discloses an exemplified form of the invention.

Considering the various figures disclosed in the drawing.

Figure 1 is a vertical sectional view of a cushioning mechanism or device embodying a form of

the present invention, a portion thereof being illustrated in elevation to more clearly disclose the structure.

Figure 2 is a horizontal sectional view taken along the lines 2—2 of Figure 1, looking in the direction of the arrows.

Figure 3 is a sectional view taken through a plane spaced below that of Figure 2 and along the lines 3—3 of Figure 1, looking in the direction of the arrows.

Figure 4 is a detailed elevational view of a portion of the device removed from the assembled structure.

Referring now in detail to the drawing, where-in like reference characters designate like parts, the numeral 1 generally indicates a cushioning mechanism or device capable of resiliently supporting a superimposed bolster or load carrying member in a railway truck as well as disturbing or breaking down synchronous or harmonic actions or vibrations created in associated bolster supporting springs during service. The compressive movement of the device 1 is resiliently and frictionally resisted while the expansive movement of the device is frictionally resisted; the resilient means being employed during the expansive movement to return the device to a normal or expanded position.

The cushioning device includes a barrel or shell member 2 being formed of a casing 3 desirably cylindrical in form and having an axially disposed bore 4. The casing 3 is open at the one or lower extremity thereof and closed at the other or top extremity by means of a cap or closing plate 5. The closing plate desirably has a centrally disposed, outwardly facing relief 5a adapted to receive a spring positioning means (not shown) to retain the upper or associated extremity of the device in a predetermined position. It will, of course, be understood that the relief may, if desired, be formed to extend entirely through the closing plate to present an aperture opening into the bore 4, and this so formed aperture may be occupied by a fabricated cap if it is desired to close the aperture to arrest the entrance of dirt or any foreign substance to within the device. The closing plate is provided with a circumambient downwardly or inwardly facing inclined surface 6 which extends outwardly of the device from the casing 3.

Movably associated with the shell member, and particularly the casing portion thereof, is a plurality of substantially counterpart segmental shoes 7 each of which comprises a stem 8 desirably formed as a ring sector in horizontal cross

section having a portion thereof extending within the casing bore 4 and provided with a cylindrical convex wearing surface 9 substantially coaxial and in bearing relation with a correspondingly formed inner concave wearing surface 10 of the casing. The stem portions merely extend into the bore a distance sufficient to allow, during service, a continued inward movement thereof so as to effect a telescoping movement of the shell member and shoes.

Each shoe includes a flange 11, preferably circular in form, extending outwardly of the device from adjacent the lower extremity of the web. Superimposed upon the flanges 11 and positioned inwardly of the device therefrom is a ring or annular member 12 adapted to carry the shoes outwardly of the device during the expanding movement thereof. The ring or annular member is provided with an undercut relief or recess 13 facing outwardly of the device to form a receptacle for the shoe flanges 11. Sufficient clearance is provided between the ring and shoes so as to allow either a free axial movement of the ring with respect to the shoes or an unrestricted radial movement of the shoes with respect to the ring without creating any abnormal strains in the device during service. The ring or annular member is provided with a circumambient inclined surface 14 facing upwardly or inwardly of the device toward the closing plate inclined surface 6.

In order to resiliently resist the compressive movement of the device as well as provide means for returning a compressed device to expanded position, a coil or helical spring 15, extending circumjacent the casing in spaced relation thereto, has end convolutions 16 thereof bearing against the shell member and ring. The coil spring employed in the instant structure is preferably of the standard American Association of Railways type of bolster supporting spring and may, if desired, comprise the outer coil of a standard double-coil spring group, the purpose of this being that the spring 15 may be associated with either an inner coil spring or a structure of the present invention. The use of this particular spring will also obviate the necessity of a specially constructed release or supporting spring.

In order to construct a cushioning device having as a part thereof a spring of the character just described, the device is constructed so as to maintain an over-all length or height substantially equal to, but desirably not greater than, the normal height of the included release spring or associated bolster supporting springs. To accomplish this purpose the end convolutions 16 are provided with outwardly facing inclined faces 17 each of which is complementarily formed and engages the inclined surfaces 6 and 14 of the closing plate and annular member respectively. In this manner, therefore, the normal height of the spring is substantially equal to the normal height of the cushioning device as well as a standard American Association of Railways bolster supporting spring, and if for any reason the spring should fail during service it may easily be replaced by a standard American Association of Railways coil spring which has its end convolutions slightly modified by grinding. Also, if for any reason it is desired to remove a cushioning device of the instant type from a railway truck and replace it by a single coil spring, the assembled device can easily be removed, dismantled and the release spring 15 replaced in operable position.

The shoes are urged radially of the device by means of an inner axially disposed cylindrical resilient member 18, preferably formed of a solid material such as, for instance, rubber, which is in bearing relation with the shoe stems. The cylinder is, when removed from the associated parts of the device, of a normal circumferential dimension greater than the normal inner corresponding dimension of the assembled shoes so that, when the cylinder is associated with the shoe stems preparatory to inserting the shoes and cylinder into the casing, the cylinder will be placed under an initial compression and thereby will be capable of urging and retaining the stem convex surfaces 9 in bearing relation with the casing concave surface 10. Any relative movement, therefore, between the shoes and shell member will create frictional forces acting upon the surfaces 9 and 10 to thereby increase the capacity of the device and also develop a period of vibration different from that of the associated bolster supporting springs. When the cylinder is removed from the device the end portions thereof are preferably formed as plane surfaces substantially perpendicular to the longitudinal axis 25 of the cylinder, and as a result thereof when the cylinder is compressed between the segmental shoes the resilient mass will flow outwardly of the end portions to form upper and lower bulged spherical convex surfaces 18^a and 18^b respectively. It will, of course, be understood that, if so desired, the end portions may be so pre-formed as to result in cylindrical convex surfaces when the cylinder is compressed between associated shoes.

Positioned intermediate the ends of each shoe 35 stem is an inwardly directed shelf or shoulder 19 which partially underlies and is in abutting relation with one or the lower surface 18^b of the cylinder. The extent to which the shelf or shoulder underlies the cylinder may be varied to any 40 desired degree, the purpose being to restrict or arrest a downward or relative shifting movement between the cylinder and shoes. Positioned intermediate each shoulder and shoe flange 11 is a reinforcing rib 20 extending inwardly of the device from each shoe stem 8.

Forming a continuation of each shoe stem 8 adjacent one or the upper extremity thereof is an angular flange 21 positioned in spaced relation to the upper surface 18^a of the cylinder and defining an axially disposed aperture 22. Interposed between the flanges 21 and the cylinder is a follower or plunger 23 having a head portion 24 normally underlying the flanges in bearing relation thereto so as to restrict the movement of the plunger in one or an upward direction. The head portion is desirably formed with a downwardly facing spherical convex surface 25 having a portion thereof bearing against the upper convex surface 18^a of the cylinder. As will be understood, the convex surface 25 may, if so desired, be formed cylindrically as it is not the present intention to limit the particular disposition of the convex surface 25 to a spherical configuration.

The follower or plunger head has extending upwardly therefrom a stem 26 which projects through the flange defining aperture 22 toward the shell end plate 5. After a predetermined compressive movement of the device the shell end plate 5 will engage the follower stem and thereby actuate the follower moving the head portion away from the flanges 21. This movement of the follower will energize the resilient cylinder and thereby form an additional resilient means to re-

sist the compressive movement of the device as well as create component radial forces which will increase the frictional force between the shoe stems and shell casing. By reason of the associated spherical convex surfaces on the follower head and cylinder end any downward movement of the follower will gradually energize the cylinder, as will be understood. It will be noted, however, that any forces tending to displace the 5 silent mass in a downward direction will result in shear stresses being developed in the cylinder due to the shelves or shoulders 18 engaging only a portion of the lower extremity 18^b of the cylinder, thus leaving a clear space or chamber 27 below the shoulders into which the resilient mass may flow.

It will, of course, be clearly understood that only an exemplified form of the invention has been illustrated and described and that numerous changes and modifications may be made thereto without departing from within the spirit and scope of the appended claims.

I claim:

1. A cushioning device comprising a shell member having a downwardly facing inclined surface, counterpart shoes each having an outwardly extending radial flange and a stem portion extending within and adapted to frictionally engage said shell member, resilient means axially disposed within said device and urging said shoes radially of said device, a ring superimposed upon said shoe flanges and provided with an inwardly facing inclined surface, and a coil spring having a normal height substantially equal to the normal height of the device, said spring having outwardly facing inclined surfaces in bearing relation with said shell member and ring inclined surfaces.

2. In a cushioning device, in combination, a barrel member comprising a casing and an end plate, counterpart segmental shoes having a stem portion extending into and adapted to frictionally engage said casing, spring means circumjacent said casing for urging said barrel member and shoes apart, each of said shoe stems having an inwardly directed shoulder intermediate the ends thereof and an inwardly directed flange adjacent one end thereof, a resilient cylinder disposed axially of said device for urging said shoes into intimate contact with said casing, said cylinder bearing on said stem shoulders, a plunger having a head portion in intimate contact with said cylinder and underlying said stem flanges, said plunger having a stem upstanding from said head and a surface on said stem in spaced relation to said end plate so that, upon a compressive movement of said device, said end plate will engage said stem surface and thereby place said cylinder in shear.

3. A cushioning device comprising a shell member having an inclined surface, counterpart shoes each having an outwardly extending radial flange and a stem portion extending within and adapted to frictionally engage said shell member, resilient means positioned between said shoes for urging them radially of said device, a ring having a downwardly facing relief for the reception of said shoe flanges and provided with an inclined surface facing said shell member inclined surface, a helical spring having a normal height substantially equal to the normal height of the device, and end convolutions of said helical spring provided with inclined surfaces in bearing relation with said shell member and ring inclined surfaces.

4. In a cushioning device, in combination, a barrel member comprising a casing and an end plate, counterpart segmental shoes having a stem portion extending into and adapted to frictionally engage said casing, spring means circumjacent 5 said casing for urging said barrel member and shoes apart, each of said shoe stems having an inwardly directed shoulder intermediate the ends thereof and an inwardly directed flange adjacent one end thereof, a resilient cylinder disposed axially of said device for urging said shoes into intimate contact with said casing, said cylinder bearing on said stem shoulders, a follower having a portion thereof underlying said stem flanges and in intimate contact with said cylinder, said follower having an upstanding portion extending outwardly of said shoes and in spaced relation to said end plate so that, upon a compressive movement of said device, said end plate will engage said upstanding portion and thereby energize said cylinder.

5. A cushioning device comprising a shell member having an inclined surface, counterpart shoes having an outwardly extending radial flange and a stem portion extending within and adapted to frictionally engage said shell member, resilient means axially disposed within said device and urging said shoes radially of said device, means engaging said resilient means and having a portion thereof spaced from said shell, a ring superimposed upon said shoe flanges and provided with an inclined surface, and a coil spring having a normal height substantially equal to the normal height of the device, said spring having inclined surfaces in bearing relation with said shell member and ring inclined surfaces, said shell being adapted to engage said means after a predetermined compressive movement of said device and thereby energize said resilient means.

6. A cushioning device comprising a shell member having an inclined surface, counterpart shoes each having an outwardly extending radial flange and a stem portion, said stem portion extending within and adapted to frictionally engage said shell member, a ring superimposed on said shoe flanges and provided with an inclined surface facing said shell member inclined surface, a helical spring having inclined surfaces in bearing relation with said shell member and ring inclined surfaces and being adapted to urge said shell member and shoes apart, end flanges on said shoes extending inwardly of said device, resilient means interposed between said shoes for urging them radially, and plunger means interposed between said shoe end flanges and resilient 55 means, said plunger means having a portion spaced from said shell member so that, after a predetermined compressive movement of said device, said shell member will engage said plunger for energizing said resilient means.

7. A cushioning device comprising a barrel member including a casing and an end plate, an inclined surface on said end plate, shoes having a portion thereof positioned within and resiliently urged into engagement with said casing, 65 an annular member associated with said shoes, an inclined surface on said annular member facing said end plate inclined surface, spring means acting between said barrel and annular members for expanding said device, and inclined surfaces 70 on said spring means in bearing relation with said end plate and annular member inclined surfaces, said spring means having a normal height substantially equal to the normal height of the device.

8. A cushioning device comprising a shell member having a casing and an end plate, segmental shoes having a portion thereof positioned within said casing, an annular member associated with 5 said shoes, spring means acting between said end plate and annular member for expanding said device, shoulders on said shoes extending inwardly of said device, resilient means interposed between said shoes for urging them into bearing 10 relation with said casing, said resilient means being in intimate contact with said shoulders, and a follower engaging the resilient means and having a portion thereof spaced from said end plate so that, upon a compressive movement of 15 said device, the follower will be actuated by said end plate and thereby energize said resilient means.
9. A cushioning device comprising a shell member having a casing and an end plate, counterpart 20 shoes having a portion thereof positioned within said casing, an annular member associated with said shoes, spring means acting between said end plate and annular member for expanding said device, shelves on said shoes extending inwardly 25 of said device, resilient means interposed between said shoes for urging them into bearing relation with said casing, said resilient means being in intimate contact with said shelves and having a convex end surface, a follower engaging the resilient 30 means convex surface and having a portion thereof adapted to be engaged by said end plate so that, upon a compressive movement of said device, the follower will be actuated by said end plate and gradually energize said resilient means.
35. 10. A cushioning device comprising a shell member having a casing and an end plate, counterpart segmental shoes having a portion thereof positioned within said casing, an annular member associated with said shoes, spring means acting 40 between said end plate and annular member for expanding said device, shoulders on said shoes extending inwardly of said device, resilient means interposed between said shoes for urging them into bearing relation with said casing, said resilient 45 means being in intimate contact with said shoulders, and a follower having a convex surface engaging the resilient means and a portion thereof directed toward said end plate so that, during a compressive movement of said device, the follower will be actuated by said end plate and gradually place said resilient means in shear.
11. In a cushioning device, in combination, a shell member comprising a casing and an end plate, segmental shoes having a stem portion 55 extending within said casing, spring means circumjacent said casing and adapted to urge said shell member and shoes apart, a shelf inwardly of said device from each of said shoes, a solid resilient cylinder interposed between said shoes 60 for urging them radially into bearing relation with said casing, said cylinder having an end convex surface, a follower having a convex surface in bearing relation with said cylinder convex surface, and a stem portion extending toward 65 said end plate so that, after a predetermined compressive movement of said device, said end plate will engage said stem portion and actuate said follower to thereby urge said cylinder into intimate contact with said shelves and gradually 70 develop shear stresses in said cylinder.
12. In a cushioning device, in combination, a shell member comprising a casing and an end plate, counterpart shoes each having a stem portion 75 extending within said casing, spring means circumjacent said casing and adapted to urge
- said shell member and shoes apart, a shoulder formed on each of said shoe stems intermediate the ends thereof, inwardly directed flanges adjacent one end of each stem spaced from said shoulders, solid resilient means having a portion thereof in bearing relation with said shoulders and adapted to urge said shoes radially into bearing relation with said casing, a follower member interposed between said stem flanges and solid resilient means, said follower and resilient means 10 each having a spherical convex surface, said follower being adapted to be actuated by said end plate and urge said follower convex surface into bearing relation with said resilient means convex surface to thereby gradually develop shear 15 stresses in said resilient means.
13. In a cushioning device, a shell member having segmental shoes movable relatively thereto, spring means urging said shell member and shoes apart, a shoulder extending inwardly of 20 said device from each shoe, a solid resilient cylinder bearing upon said shoulders and urging said shoes radially of said device into intimate contact with said shell member, and movable plunger means engaging said cylinder, said plunger being 25 adapted to be actuated by said shell member for developing shear stresses in said cylinder.
14. In a cushioning device, a shell member having counterpart shoes movable relatively thereto, spring means urging said shell member and shoes apart, a shelf extending inwardly of 30 said device from each shoe, a rubber cylinder bearing upon said shelves and urging said shoes outwardly of said device into bearing relation with said shell member, and a follower engaging 35 said cylinder, said follower having a portion thereof spaced from and adapted to be engaged by said shell member so that, upon a predetermined compressive movement of said device, said follower will be actuated by said shell member 40 and thereby develop shear stresses in said cylinder.
15. A cushioning device comprising a shell member having an inclined surface, a plurality of shoes each having a stem portion extending 45 within and adapted to frictionally engage said shell member, resilient means positioned between said shoes for urging them radially of the device, a ring associated with said shoes and provided 50 with an inclined surface facing said shell member inclined surface, a helical spring having a normal height substantially equal to the normal height of the device, and end convolutions of said helical spring provided with inclined surfaces in bearing 55 relation with said shell member and ring inclined surfaces.
16. In a cushioning mechanism, a shell member having segmental shoes movable relatively thereto, means for urging said shoes into engagement with said shell member, means associated with 60 said shoes, spaced confronting inclined surfaces on said shell member and second-named means, and resilient means of a normal height substantially equal to the normal height of the mechanism acting between said shell member and shoes 65 for urging them apart, said resilient means having inclined surfaces in bearing relation with said confronting inclined surfaces.
17. In a cushioning device having relatively 70 movable elements, said elements having substantially confronting inclined surfaces at opposed extremities of the device, spring means having a normal height substantially equal to the height of said device, and inclined surfaces on said spring means in engagement with said confronting in- 75

clined surfaces, said spring means being adapted to urge said relatively movable elements apart.

18. A shell member for use in a cushioning device comprising a casing for the reception of relatively movable elements and an end plate associated with one end of said casing, said end plate having an inclined surface for engagement by a correspondingly formed surface of an associated spring means so that said end plate and spring means will present a substantially flat bearing surface.

19. An annular member for use in a cushioning device, said annular member having an inner recess for the accommodation of associated parts of

15 friction shoes, and an outer inclined surface for engagement by a correspondingly formed surface of an associated spring means so that said annular member will be positioned substantially within the confines of said spring means.

20. In a cushioning device, a shell member having segmental shoes movable relatively thereto, spring means urging said shell member and shoes apart, a resilient cylinder within said shoes urging them radially of the device into intimate contact with said shell member, a convex surface on said cylinder, and movable means associated with said convex surface, said movable means being adapted to be actuated by said shell member to thereby gradually energize said cylinder.

30. 21. In a cushioning device, in combination, a barrel member having segmental shoes movable relatively thereto, spring means urging said barrel member and shoes apart, a resilient cylinder within said shoes adapted to urge them radially 35 of the device into intimate contact with said barrel member, and movable means having an articulate surface associated with said cylinder, said movable means being adapted to be actuated during a compressive movement of said device to thereby gradually energize said cylinder.

40. 22. In a cushioning device, in combination, a shell member having shoes movable relatively thereto, spring means urging said shell member and shoes apart, a shoulder extending inwardly 45 of said device from each of said shoes, a resilient cylinder bearing upon said shoulders and urging said shoes radially of said device into intimate

contact with said shell member, and means associated with said device so that, upon a compressive movement of said device, said means will be actuated to develop shear stresses in said resilient cylinder.

5. 23. A shoe for use in a cushioning device having, in combination, a stem adapted to frictionally engage an associated shell member, a flange adjacent one end of said stem, a shoulder intermediate the ends of said stem forming an abutment for an associated resilient means, and a flange directed oppositely from said first-named flange and positioned adjacent the other end of said stem.

10. 24. In a cushioning device, in combination, a shell member having housing forming shoes movable relatively thereto, spring means urging said shell member and shoes apart, a resilient cylinder positioned within said shoe housing and being, when removed from the device, of greater 15 circumferential dimension than the normal circumference of said housing so that, upon application of said resilient cylinder to said housing, it will be initially compressed to thereby urge said shoes into intimate contact with said shell member, and movable means retained in a predetermined position by said shoes and adapted to energize said resilient cylinder upon a compressive movement of said device.

25. 25. In a cushioning device, in combination, a shell member having shoes movable relatively thereto, spring means urging said shell member and shoes apart, a resilient cylinder interposed between said shoes and being, when removed from the device, of greater horizontal dimension 30 than the distance between said shoes so that, upon application of said resilient cylinder to said device, it will be initially compressed to thereby urge said shoes into intimate contact with said shell member, shoulders extending inwardly of 35 said device from said shoes and forming a bearing for said resilient cylinder, and movable means actuated upon a compressive movement of said device to develop shear stresses in said resilient cylinder.

40. 45. EMIL H. BLATTNER.
